UNITED STATES PATENT OFFICE.

FRANK L. FELTES, OF CLEVELAND, OHIO, ASSIGNOR, BY MESNE ASSIGNMENTS, TO ALUMINUM COMPANY OF AMERICA, OF PITTSBURGH, PENNSYLVANIA, A CORPORATION OF PENNSYLVANIA.

MOLDING MACHINE.

Application filed December 13, 1926. Serial No. 154,518.

This invention relates to molding machines and particularly to that class of such devices employed in casting soft metal pistons, or the like, and is of the same general 5 nature as the machine disclosed in my co-pending application Serial No. 87,827, filed February 12, 1926.

In a machine of the type to which reference has been made, owing to the conformation of the casting desired it is necessary not only to split the mold but also to employ a built up core, that is, one consisting of a number of pieces which when properly arranged make up the desired core form but 15 which require progressive individual insertion into and withdrawal from the mold. Also in casting pistons it is customary to employ core pins inserted and removed laterally through the mold for the purpose of 20 forming the wrist pin bearings.

In casting the core parts, being substantially surrounded by the casting metal, attain a much higher temperature than do the mold parts which surround the casting 25 metal, and it is found that the mold parts are capable of performing their function at a much higher rate of speed than the core parts. For this reason certain machines have been devised in which a multiplicity of 30 duplicate core units are arranged to successively serve the same mold parts, so that the intervals between functioning of the individual core units allow sufficient time for 35 cooling of the same. In such machines the core parts with their actuating mechanisms which comprise the core units are for the most part necessarily movable progressively with respect to the mold and where a number of core units must thus be advanced in 40 a rapid succession were the casting machine to be made operable only by hand as before a great deal more labor is required, in proportion to the multiplicity of cores employed.

It is an object of this invention to provide in a machine of the class described, power means for operation of the core mechanism in an arrangement in which not only the several core units may be successively 45 aligned with the mold but also the cores inserted into and withdrawn therefrom, the ultimate object being a much more rapid operation of the machine than has been possible with hand manipulation.

A further object is to provide what might 55 be termed semi-automatic operation of the core pins, that is, means for doing away with hand indexing or aligning of the core pins for insertion into the core.

Still another object of the invention is to 60 provide power means for maintaining the mold closed, that is the parts of the mold in proper contact during the casting operation; all of the objects above named being accomplished in a manner best adapted for application to a machine of the peculiar nature 65 and subject to the limitations described.

Further objects and advantages accruing from my invention will be apparent from the following description taken in connection 70 with the accompanying drawings, in which Fig. 1 is a side elevation of the machine of the type to which reference has been made, with my improvements incorporated therein; Fig. 2 is a plan view of the 75 same machine; Fig. 3 is a sectional elevation along the line 3—3 of Fig. 1; Fig. 4 is a vertical section of the pertinent parts taken along the line 4—7 of Fig. 2 showing details 80 of the core operating gears; Fig. 5 is a horizontal section along the line 5—5, Fig. 4; Fig. 6 is a horizontal section along the line 6—6 of Fig. 4; Fig. 7 is a section along the line of 4—7 of Fig. 2 showing details other than those appearing in Fig. 4; Fig. 8 is a 85 detail of the core pin turret operating mechanism, and Fig. 9 is a horizontal section along the line 9—9 of Fig. 8.

Referring now to the drawings, the principal parts of the machine are a frame 1 raised at its forward portion to support a mold forming unit, and at its rear portion extending upward to support a turret head upon which are mounted a number of core forming units adapted for rotation to successively register with the mold forming unit.

Across the forward raised portion of the frame is a heavy member 8 forming a table and provided with a finished upper surface. Slidably mounted upon the surface and suitably guided thereon are a pair of mold members 14 adapted for cooperation when closed upon each other to form a cylindrical mold, the plane of parting being on the diameter of the cylinder; the forward portions of these parts are extended to form 100 when in contact a sprue 14' leading to the

cylinder cavity. Beneath the table is a rock shaft 4 movable by the lever 5 and connected by suitable linkage members 50 to 54 with the mold members 14 in such a manner that movement of the lever 5 in one direction, as to the right, Fig. 3, will slide the members apart on the table to open the mold, and in the other direction will bring them together as in the position shown.

At each side of the table is a turret 38 provided with radially extending core pins 31 adapted for insertion into corresponding laterally extending holes in the inner member 14, the turrets being aligned with these holes are movable laterally upon the table. The core pins 31 are provided in multiple as shown so that they may be used in succession by rotation of the turrets to thus allow for cooling of the idle pins. Cooling of the remaining portion of the mold is effected largely by conduction by the relatively large masses of metal, especially in the table 8 which will be noted as forming the bottom closure of the mold as well as supporting means for the members 14 in all positions.

My invention embraces among other things means for automatically indexing the turrets 38 so that by manipulation of the lever 5 to open and close the mold the core pins 31 will be swung around progressively for successive entry into the mold.

The turrets 38 are mounted for rotational movement in carriages 101 slideable laterally upon the table 8 and positioned thereon so that the center lines of the turrets are in a plane with that of the piston cavity in the mold. Each carriage 101 is connected with one of the levers 50 through a link 102 whereby the turrets are advanced to the mold and the aligned core pin 31 projected thereto upon movement of the lever 5 to close the mold. Fixed upon each turret axis is a ratchet wheel 103. Pivotal secured in the plane of each ratchet wheel and urged to engagement with the ratchet wheel by a spring as indicated is a detent member 104 bearing teeth upon a portion of its ratchet wheel engaging surface as indicated. The arrangement is obviously such that as each turret 38 is moved away from the mold to clear a member 31 the teeth upon the detent member will engage those upon the ratchet wheel to effect rotation thereof, and the proportions of parts is such that this rotation will be in an amount corresponding with the number of core pins provided; in the embodiment illustrated four core pins being provided upon each turret, the turrets will be rotated 90° at each opening of the core.

At the ends of the table 8 upon suitable brackets 105 are mounted a pair of cylinders 106 containing pistons in connection with piston rods 107 adapted to abut the members

14 of the mold. The cylinders 106 are interconnected as by a pipe 108 and with a suitable source of fluid pressure controlled by a valve 109. The object of this arrangement is to maintain the mold securely closed during the casting operation; and its mode of functioning will be apparent. After closing the mold by proper manipulation of the lever 5 the valve 109 is opened admitting fluid pressure through the pipe 108 through the cylinder 106 and forcing the piston rods 107 against the mold parts 14, thus making the pressure effective upon the piston areas to hold the mold forcibly closed while casting. After the casting operation the valve 109 is turned to release the pressure within the cylinders whereupon the mold may be reopened by the lever 5.

The machine illustrated is provided with four core units the primary member of each of which is a core 67 adapted to correspond with the mold and comprising a number of separate members requiring insertion and withdrawal in proper sequence. In my co-pending application, Serial No. 72,276, filed Nov. 30, 1925, (Patent No. 1,663,693), I have minutely described this sectional core as well as the immediate means for its operative assembly and disassembly. Generally this sectional core assembly comprises a plurality of separable core elements, the periphery of the assembled units being configured to produce a matrix for the inner surface of the casting. These core elements are provided with arms which converge in a common plane vertically disposed in relation to the mold members 14 and aligned therewith. Each arm is affixed to and supported by a rod 57 guided in a bearing formed in an arm 55 extending from a turret head adapted for rotational movement upon a vertical journal carried by the frame 1. The upper ends of the rods 57 are united through linkage 73 to pivotally supported levers 71 the movement of which is controlled by cam wheels affixed to a shaft 75 journaled in the arms 55. The shaft 75 is associated with a vertically disposed shaft and suitable gearing to effect its rotative movement as will be hereinafter explained, the organization of this gearing, however, is provided to rotate the cam wheels and thus reciprocate the shafts 57 effecting the desired insertion or withdrawal of the core assembly with the mold members 14. The arms 55 may be formed integral with the turret head, as shown, but in any event they are secured together to form a unitary structure adapted for rotational movement upon a vertical axis, as indicated in Figure 7, and for successive registry of the cores above the mold.

According to my invention a motor 110 is secured upon the rear upstanding portion of the base member 1 as indicated and operatively connected with a ring gear 111 con-

centric with the axis of the turret bearing the members 55, as through suitable speed reducing gears and the jack shaft 112. The gear 111 is supported by a suitable bearing 5 shoulder on the base and normally runs free of both the base and the turret members 55. On the lower surface of the ring gear is cut a set of bevel teeth meshing with the bevel pinion 113 upon a radial shaft extending 10 within the gear box 114 and carrying at its opposite extremity a bevel gear 115 meshing with a pair of bevel gears 116 and 116' free upon a vertical shaft 117 to run in opposite directions in the gear box 114 which is fixed with the base 1. A collar 118 secured on the turret with the members 55 extends downwardly adjacent the gear 111 and carries a number of spaced friction members 119 each urged to engagement with 15 the upper finished surface of the gear by a spring 120, the total friction of the members 119 being sufficient to normally effect rotation of the members 55 with the gear 111 which moves very slowly owing to the 20 speed reduction means described.

Upon each of the members 55 is secured a finger 121 the lower surface of which is finished and extends in a horizontal plane above the gear box 114. Mounted for vertical movement in the gear box is a rod 122 controllable by a handle 123 but normally urged upwards by the spring 124 to a position in which the rounded head of the rod projects as indicated in Fig. 4, upward movement 30 of the rod being limited as by the nut 125 bearing against the gear box. In this position of the rod 122 its upper end is slightly above the plane of the lower surfaces of the members 121. The forward 35 portions of these surfaces are beveled off as at 121' to form cams adapted to engage the rod 122 to force it downwards until it rests beneath the member 121 advanced against it by rotation of the turret.

In each of the members 121 is a depression 45 124' adapted to fit the upper extremity of the rod 122 in the position indicated in Fig. 4 and circumferentially spaced such that when engaged by the rod its corresponding 50 core 67 will be vertically aligned above the mold.

What has been just immediately described is operative to rotate and automatically index the cores in succession as follows: Assuming 55 one of the cores in alignment with the mold as after completion of a casting operation the rod 122, engaging the depression in one of the members 121, will arrest further rotating movement of the collar 118 and its appurtenances as this engagement is sufficient to overcome the tendency of the friction members 119 to effect rotation of the members 55.

Downward movement of the handle 123 60 withdraws the rod 122 relieving its detent

action upon the member 121 and allowing rotational movement of the members 55 with the gear 111 until, subject to release of the handle 123, the next member 121 is engaged to position the next core in operative relation with the mold. 70

Associated with each of the gears 116 and 116' is a clutch member 126 of the expandable ring type adapted upon rotational movement of a wedge member 127 positioned 75 between the ends of the member 126 to frictionally engage a suitable cylindrical inner surface upon the gear to secure the same with the shaft 117. Each of the members 127 is secured with a lever arm 128 the end 80 of which is adapted for engagement with a conical surface upon the clutch control member 129. The member 129 is movable vertically upon the shaft 117 by means of the usual yoke 130 fitting within a groove 85 upon the same and connecting with a control lever terminating in a handle 131 outside the gear box. The result of the arrangement described is that upward movement of the handle 131 will effect rotation of the 90 shaft 117 in one direction and downward movement of the handle will effect reversal of the shaft, the mid-position of the handle allowing the shaft 117 to idle. Buttons are provided, as indicated in Fig. 7, for normally maintaining the handle 131 in any of its three described positions. 95

Upon the upper extremity of the shaft is a pinion 132 adapted as each of the members 55 is properly indexed, to mesh with a pinion 100 133 upon a vertical shaft 134, mounted on the arm 55. Each of the arms 55 is provided with one of these shafts 134, the upper extremity of which carries a gear meshing with a gear upon the shaft 75. Obviously 105 therefore when any of the members 55 is indexed a drive is provided for the shaft 75 from the motor 110 and subject to the control of the handle 131 to raise or lower a core through the mechanism carried by the 110 arm 55 and already described.

Initiation of either the core lowering or core raising movement is by the handle 131, but I have provided means for automatically terminating rotation of shaft 75 at the proper time for completing the motion, as follows: Connecting with the lever which carries the handle 131 is a vertically slidable rod 135 terminating in a head 136 as indicated. Upon each of the members 55 is mounted 115 in a bracket 137 a vertically movable rod 138 terminating at its lower extremity in a member 139 of conformation adapted when the arm 55 is indexed, to fit around the head 136, with some vertical clearance as indicated in Fig. 1. The weight of the rod 138 is counterbalanced by the spring 140. The upper end of the rod carries a finger 141 resting in the position shown, upon a pin 142 laterally projecting from the inner core- 120 125 130

operating cam; another finger 143 is also secured upon the rod 138 in the plane of the bent arm of the lever 144, the opposite arm of which extends into the plane of the pin 142. The arrangement is such that assuming the parts positioned as indicated in Fig. 1 upward movement of the handle 131 will move the member 129 upward to start the core operating mechanism to insert the core 10 into the mold, which will move the head 136 upward to just contact upon its upper surface with the member 139. As the pin 142 moves with its cam in a counterclockwise direction, Fig. 1, it will ride around to contact with the lever 144 to move the same in a counterclockwise direction as the core attains its casting position. Movement of the lever 144 effects through the arm 143 downward motion of the rod 138 to effect through 15 the members 135, 131 and 129 declutching 20 of the core actuating mechanism.

Likewise subsequent downward movement of the handle 131 will effect withdrawal of the core 67 from the mold and as the pin 25 142 attains the position illustrated, upward movement of the rod 138 to again return the handle 131 to neutral position.

What I claim is:

1. In a molding machine, a base, a mold 30 thereon, a head mounted for rotation upon said base, a plurality of core units carried by said head and adapted for rotation therewith to successive alignment with said mold, means for inserting an aligned core into said 35 mold and for withdrawing the same therefrom, and power means for rotating said head and indexing the same to align said cores, comprising a motor secured upon said base, a ring gear mounted upon said base 40 adjacent said head, an operative connection between said motor and said ring gear whereby the latter is normally maintained rotating slowly, friction means whereby said head tends to rotate with said ring gear, 45 means for detaining said head in aligned position of any of said cores, and means for releasing said head for rotation from said position.

2. In a molding machine, a base, a mold 50 thereon, a head mounted for rotation upon said base, a plurality of core units carried by said head and adapted for rotation therewith to successive alignment with said mold, means for inserting an aligned core into said 55 mold and for withdrawing the same therefrom and power means for rotating said head and indexing the same to align said cores, comprising a motor secured upon said base, a ring gear mounted upon said base 60 adjacent said head, an operative connection between said motor and said ring gear whereby the latter is normally maintained rotating slowly, friction means whereby said head tends to rotate with said ring gear, 65 means for automatically engaging said head

to detain the same in aligned position of any of said cores, and means for releasing said head for rotation from said position.

3. In a molding machine, a base, a mold 70 thereon, a head mounted for rotation upon said base, a plurality of core units carried by said head and adapted for rotation therewith to successive alignment with said mold, each core unit including a train of mechanism carried by said head for inserting 75 an aligned core into said mold and for withdrawing the same therefrom, and power means for accomplishing the functions named, comprising a motor secured upon said base, a ring gear mounted upon said 80 base adjacent said head, gearing operative between said motor and said ring gear whereby the latter is normally maintained in rotation at a slow speed, friction means whereby said head tends to rotate with said 85 ring gear, means automatically detaining said head in aligned position of any of said cores, means for releasing said head for rotation from said position, means on said 90 base actuated by said ring gear for controlling the operation of said train of mechanism, and means carried by said head in connection with said train of mechanism and engageable with said controlling means 95 for actuation subject to said control means of a core in said aligned position thereof.

4. In a molding machine, a base, a mold 100 thereon, a head mounted for rotation upon said base, a plurality of core units carried by said head and adapted for rotation therewith to successive alignment with said mold, each core unit including a train of 105 actuating mechanism carried by said head for inserting an aligned core into said mold and for withdrawing the same therefrom, and power means for accomplishing the 110 functions named, comprising a motor secured upon said base, a ring gear mounted upon said base adjacent said head, gearing operative between said motor and said ring gear whereby the latter is normally maintained in rotation at a slow speed, friction means whereby said head tends to rotate with said 115 ring gear, means automatically detaining said head in aligned position of any of said cores, means for releasing said head for rotation from said position, means on said base actuated by said ring gear for controlling the operation of said train, means carried by said head in connection 120 with said train and engageable with said controlling means for actuation subject to said control means of a core in said aligned position thereof, means on said head for initiating the operation, through said controlling mechanism, of said train to insert or withdraw a core in said mold, and a connection between said train and said control means for automatically terminating said 125 core movement at its completion.

5. In a molding machine, a base, a mold thereon, a head mounted for rotation on said base, a plurality of core units carried by said head and adapted for rotation there-
5 with to successive alignment with said mold, each core unit including a train of mechanism having definite cycles of operation for inserting an aligned core into said mold and for withdrawing the same therefrom, said
10 mechanism being carried by said head, a motor secured upon said base, a ring gear mounted upon said base adjacent said head, an operative connection between said motor and said ring gear whereby the latter may
15 be maintained in rotation at a slow speed, friction means whereby said head tends to rotate with said ring gear, means automatically detaining said head in aligned position of any of said cores, means for releasing
20 said head for rotation from said position, a pinion mounted for rotation on said base, gears and clutches adapted to drive said pinion in either direction from said ring gear, a handle for controlling said
25 drive, pinions in operative connection with each of said trains of mechanism and adapted to mesh with said first named pinion as their respective cores are aligned with said mold whereby the train of mechanism op-
30 erating said core may be driven, subject to said handle, by said ring gear, to operate its core, a member of each of said trains of mechanism being adapted, in aligned posi-
tion of said core, to disengage the drive to said first named pinion upon completion of 35 an inserting or withdrawing movement of said core.
6. In a molding machine, a mold, a core pin receiving aperture therein, a plurality of core pins adapted for successive cooperation 40 with said aperture, said core pins being radially arranged upon a turret, said turret being movable in relation to said mold axially of said aperture to insert or withdraw a pin therein, and means dependent upon 45 said movement of said turret for rotating the same to replace a pin aligned with said aperture.
7. In a molding machine, a mold, a lever for opening and closing the same, a core pin 50 receiving aperture in said mold, a plurality of core pins adapted for successive co-
operation with said aperture, said core pins being radially arranged upon a turret, said turret being movable in relation to said 55 mold, axially of said aperture to insert or withdraw a pin therein, a connection be-
tween said lever and said turret to effect said movement, and means dependent upon said movement for rotating said turret to 60 replace a pin in alignment with said aper-
ture.

In testimony whereof I hereby affix my signature.

FRANK L. FELTES.
